UNITED STATES PATENT OFFICE.

THOMAS PATES, OF ALTON, ILLINOIS, ASSIGNOR TO THE HAPGOOD PLOW COMPANY, OF SAME PLACE.

PLANTING-PLOW.

SPECIFICATION forming part of Letters Patent No. 249,790, dated November 22, 1881.

Application filed July 7, 1881. (No model.)

To all whom it may concern:

Be it known that I, THOMAS PATES, of Alton, in the county of Madison and State of Illinois, have invented a new and useful Improvement in Planting-Plows, which improvement is fully set forth in the following specification and accompanying drawings.

My invention relates to improvements in planting-plows in which the planting attachments are assembled and supported on a bent beam and adapted for use in a sulky planting-plow.

My invention consists, first, in an improved construction of the drill-tooth stock; and, second, in the construction of the center bar, to which the stock is attached; and, third, in the arrangement and combination as hereinafter shown.

In the drawings my improvements are illustrated attached to a listing planting-plow, in which—

Figure 1 is a vertical sectional view of a planting-plow with my improvements shown, and showing how they are arranged and combined with the beam and plow. Fig. 2 is a top view of that part of Fig. 1 below the dotted lines *x x*. Fig. 3 is a view of the drill-tooth stock *C*, enlarged, showing my improvements, the groove *c* and the keeper *e*. Fig. 4 is a cross-section view taken on the dotted lines *z z* of Fig. 3. Fig. 5 is a view of the center bar, *a*, showing its construction and showing the upright part *b*.

Similar letters refer to similar parts throughout the several views.

C is my improved drill-tooth stock, having a perforation throughout, "pipe-like," from top to bottom, through which the corn passes from the dropping-box, and on the lower part of the stock a steel tooth or blade, *C'*, is attached, as shown; and on the front side of the stock I make a groove, *c*, and on the rear side I make a keeper, *e*. The purpose of the groove is to keep the drill-tooth stock perpendicular by embracing the sides of the upright *b*, and the purpose of the keeper *e* is to keep the stock from dropping away from the clasp holding the stock in place, as hereinafter set forth.

a is my improved center-bar, consisting of a bar of iron having its forward end fitted to support the share of the listing-plow *W*, and on the rear part of the center-bar I make a bend upright, *b*, to which the stock *C* is at-

tached, as shown. The center-bar, *a*, is attached to the bottom end of the beam *A* with 55 bolts or rivets, as shown in Fig. 1, the bottom end of the beam being set off from the center to admit the center-bar to occupy the center of the plow. The center-bar *a* is secured in position as shown in Fig. 1, and the groove 60 *c* embracing the uprights *b* with a two-nutted *U*-clasp, securing the stock *C* in its position, the clasp passing through perforations in the shovel-beam *k*, as is clearly shown in the drawings.

The drill-tooth *C'* may be adjusted up and down by a movement of the groove *c* on the upright *b*; and should any loosening of the nuts on the *U*-clasp occur, whereby the tooth and stock may drop, the keeper *e* would rest 70 on the top of shovel-beam *k*, keeping it from being lost out of its position.

In operation the listing-plow *W* throws its furrow-slice both ways, cleaning a wide furrow, the drill-tooth *C'*, adjusted to enter the 75 subsoil, throwing open a narrow furrow, into which the corn is dropped through the stock *C*, and the shovels *P P* covering the corn by returning the loose soil thrown out by the drill-tooth. The groove *c*, sliding on the upright 80 *b*, affords a simple and ready means of adjusting the drill-tooth to any desired depth into the subsoil, and the center-bar *a* provides for securing the drill-tooth and covering-shovels closely following the plow, and not easily to 85 get out of order.

Having thus set forth my invention, I claim as follows:

1. In a planting-plow, the hollow pipe-like drill-tooth stock *C*, supporting on its lower 90 part a blade or tooth, *C'*, and having a groove, *c*, extending along its front side above the blade *C'*, as shown, and for the purpose specified.

2. In a planting-plow, the center-bar *a*, constructed with the bend part *b*, extending upright and supporting the drill-tooth stock, as shown, in combination with the beam *A*, and the drill-tooth stock *C*, and the groove *c* of the stock *C*, embracing the sides of the part *b*, as 100 shown.

THOMAS PATES.
